(57) **CLAIM**

An ornamental design for a hot air gun, as shown and described.

DESCRIPTION

FIG. 1 is a front side perspective view illustrating the hot air gun showing my new design;

FIG. 2 is a rear side perspective view illustrating the hot air gun showing my new design;

FIG. 3 is a rear perspective view of the hot air gun shown in FIGS. 1 and 2;

FIG. 4 is a top perspective view of the hot air gun shown in FIGS. 1 and 2;

FIG. 5 is a bottom perspective view of the hot air gun shown in FIGS. 1 and 2;

FIG. 6 is a first side perspective view of the hot air gun shown in FIGS. 1 and 2; and,

FIG. 7 is a second side perspective view of the hot air gun shown in FIGS. 1 and 2.

The broken lines in the FIGURES depict portions of the hot air gun that form no part of the claimed design.
